UNITED STATES PATENT OFFICE.

BERT CONWAY SWAGGERT, OF EUREKA, CALIFORNIA.

AUTOMATIC RELEASE-PULLEY.

No. 839,228.

Specification of Letters Patent.

Patented Dec. 25, 1906.

Application filed June 28, 1906. Serial No. 323,766.

To all whom it may concern:

Be it known that I, BERT CONWAY SWAGGERT, a citizen of the United States, residing at Eureka, in the county of Humboldt and State of California, have invented a new and useful Automatic Release-Pulley, of which the following is a specification.

This invention relates to pulleys of that type designed to release the line by an enlargement on the latter—such, for instance, as the eye or loop at the end thereof to which the hook or other fastening device is attached—the enlargement being adapted to engage with a suitably-hinged part of the pulley-block, so as to release a keeper and permit the cable to be disengaged.

The objects of the invention are to simplify and improve the construction and operation of this class of devices, so as to render them reliable and effective.

With these objects in view and others, as will appear as the nature of the invention is better understood, the invention comprises the various novel features of construction and arrangement of parts described herein-after and set forth with particularity in the claims appended hereto.

In the accompanying drawings, which illustrate one of the embodiments of the invention, Figure 1 is a perspective view of the pulley, showing the same employed in connection with a lifting-line. Fig. 2 is a similar view showing the hinged part of the block and the keeper opened to permit the line to be released. Fig. 3 is a sectional view of the keeper or yoke and adjacent parts. Fig. 4 is a partial side elevation of the device, showing the means for enabling an enlargement on the line to actuate the hinged section of the block.

Corresponding parts in the several figures are indicated throughout by similar characters of reference.

Referring to the drawings, A designates the block of the pulley, and B the sheave, mounted in the block and rotatable on the journal a. The block comprises side plates 1 and 2, connected and spaced apart by the rivet-pins 3, and the journal a, which preferably takes the form of a bolt. The side plate 2 is constructed in two sections 4 and 5, that are provided with overlapping lugs 6 on their outer surface that are perforated to receive the pintle 7, whereby the section 5 is hinged on the section 4 and is capable of swinging outwardly with respect to the

sheave. The hinged section 5 is arranged at the upper part of the block and projects at its upper end a suitable distance above the highest point of the sheave B. The side plate 1 also extends upwardly above the sheave and is provided with bifurcations 8, between which is pivoted a keeper or yoke 9, the pintle 10 of which extends through perforations in the bifurcations. The free end 65 of the keeper is adapted to be embraced by the hinged section 5, which is provided with an opening 10' to receive the end of the keeper, as shown in Figs. 1 and 3. The keeper is provided at a medial point with an 70 opening 11, which is adapted to receive a hook or any other suitable means for suspending the pulley.

In order to hold the hinged section 5 and the keeper in a normal or operative position, 75 a spring-latch 12 is employed, the same comprising a strip of elastic material, such as steel, which is anchored at one end in a recess 13 in the bottom side of the keeper at the free end thereof and at its outer end is formed 80 into a projection or nose 14, that is adapted to engage the outer surface of the hinged section 5 at the point indicated by 15. The edge of the opening 10' at 15 is slightly rounded, so that the latch will readily release the section 5 when lateral pressure is exerted on the latter. In order to permit the latch to be withdrawn by hand, the outer end is formed 85 into an upwardly-extending hook 16, disposed along the end surface of the keeper. 90 The nose 14 is so shaped that when sufficient pressure is brought to bear upon the hinged section tending to swing it outwardly the latch will yield or move into the recess 13 of the keeper, thereby disengaging the nose 95 from the hinged section.

Pressure for opening the hinged section is derived from an enlargement on the line 17, such enlargement being a splice 18 for forming the loop 19 of the line. The enlargement, which of course may be any other suitable means than the splice, is adapted to enter a wedge-shaped passage 20, formed by the extension 21 on the plates 1 and 2, as shown in Figs. 1 and 4. At the inner or narrowest end of the wedge-shaped passage is the hinged section 5. By this arrangement the enlargement on the line, which latter may be a wire cable or rope of any other material, is adapted to wedge into the narrowest part 105 of the passage, and thereby exert a lateral pressure on the hinged section. When this

pressure becomes greater than the holding effect of the spring-latch, the hinged section and keeper are released, thereby permitting the line to fly out of the pulley.

- 5 From the foregoing description, taken in connection with the accompanying drawings, the advantages of the construction and of the method of operation will be readily appreciated by those skilled in the art to 10
 10 which the invention appertains. In certain pulley constructions with which I am acquainted it happens that the line is pulled too far into the block, so that the eye, hook, or other attaching means thereon becomes
 15 wedged between the parts of the block, resulting in the parts being spread out of shape and rendering it difficult to release the line. Such and other incidental difficulties are successfully overcome with the present construction.

20 While I have described the pulley in connection with a lifting-line, it is of course obvious that the pulley may be used in connection with a cable or rope that conveys a carriage. In this case the pulley will be opened by an enlargement on the cable, so as to permit the carriage to pass without the pulley interfering therewith, as will be readily understood.

25 30 I have described the principle of operation of the invention, together with the apparatus which I now consider to be the best embodiment thereof; but I desire to have it understood that the apparatus shown is merely 35 illustrative and that various changes may be made, when desired, as are within the scope of the invention.

What is claimed is—

1. The combination of a block having a 40 hinged section provided with an opening, a keeper hinged on the fixed part of the block and adapted to engage at its free end in the opening of the hinged section, a yielding locking means on the keeper for engaging the hinged section to hold the latter and keeper in a closed position, a sheave mounted in the block, a line riding on the sheave and provided with an enlargement, and coöperating walls on the block arranged to be engaged by 45
 50 the enlargement to exert an opening pressure on the hinged section.

2. The combination of a block having a hinged section provided with an opening, a keeper attached to a fixed part of the block 55 and adapted to engage in the opening of the hinged section, a line having an enlargement,

means on the block arranged to be engaged by the enlargement of the line for automatically opening the keeper, and means for holding the keeper and section in a closed position and permitting them to automatically open, said latter means comprising a resilient member attached at one end to the keeper and provided with a nose at its free end for yieldingly engaging the said section. 60 65

3. The combination of a block having a hinged section provided with an opening, a keeper attached to a fixed part of the block and adapted to engage in the opening of the hinged section, and means for holding the keeper and section in a closed position, said means comprising a resilient member attached at one end to the keeper and provided with a nose at its free end for yieldingly engaging the said section and with a hook extending from the nose along the end of the keeper. 70 75

4. A block comprising two connected side plates, one of which plates being provided with a bifurcated portion and the other with a hinged section having an opening, in combination with a keeper arranged at one end between the bifurcations of the one plate, a pintle extending through the bifurcated portion and keeper and arranged to permit the latter to engage at its free end the opening of the hinged section, a pulley mounted on the block, a line having an enlargement, a locking device for yieldingly holding the keeper and hinged section closed, and means on the block engaged by the enlargement of the line for opening the hinged section and keeper to permit the line to be released from the block. 80 85

5. A block comprising two side plates having opposed walls coöperating to form a wedge-shaped passage, a hinged member arranged at the narrowest end of the passage, a keeper on the block, means for yieldingly holding the keeper and hinged member together, a pulley mounted on the block, and a line riding on the pulley which is provided with an enlargement for entering between the said walls and wedging against the hinged member so as to exert a pressure to release the latter. 90 95 100 105

In testimony that I claim the foregoing as my own I have hereto affixed my signature in the presence of two witnesses.

BERT CONWAY SWAGGERT.
